UNITED STATES PATENT OFFICE.

CHARLES HUGH DUFFY, OF CHEVY CHASE, MARYLAND.

CALCULATOR.

1,161,381.

Specification of Letters Patent. Patented Nov. 23, 1915.

Application filed March 9, 1915. Serial No. 13,175.

To all whom it may concern:

Be it known that I, CHARLES HUGH DUFFY, a citizen of the United States, residing at Chevy Chase, in the county of 5 Montgomery and State of Maryland, have invented certain new and useful Improvements in Calculators; and I do declare the following to be a full, clear, and exact description of the invention, such as will enable others skilled in the art to which it 10 pertains to make and use the same, reference being had to the accompanying drawings, and to the letters and figures of reference marked thereon, which form a part 15 of this specification.

This invention relates to the class of calculators but more particularly to a device for adding, subtracting, dividing and multiplying two figures, the same being 20 arranged in such manner that the sum, the difference, the result and the quotient of the addition, subtraction, multiplication and division of two numbers will be simultaneously indicated.

25 The invention consists in the arrangement of two disks pivoted centrally so as to be capable of relative rotation, the under disk having thereon marginal numbers spaced one from the other and having opposite 30 each marginal number the sums, the differences, the results and the quotients of said number and any other marginal number appearing on the upper disk, the said upper disk being provided with marginal numbers 35 and opposite to each marginal number an opening or series of openings so cut therein as to uncover the numbers on the lower disk forming the sum, the difference, the result and the quotient of two numbers, one of 40 which is a marginal number on the lower disk, the other of which is a marginal number on the upper disk.

Referring to the accompanying drawing Figure 1 is a plan view of the device. Fig. 45 2 is a plan view of the lower disk, and Fig. 3 is a fragmentary sectional view illustrating the pivoting of the two disks.

Like numerals of reference indicate the same parts throughout the three figures. 50 For a more ready and simple illustration of this invention the device illustrated in the accompanying drawing has been limited to Figs. 1 to 5, as the same is clearly sufficient to illustrate the construction and principle of the invention and any additional figures would unduly complicate the illus-

tration, and would add nothing to a clear understanding of the invention. Although it is to be clearly understood that the marginal numbers on the disks can run from 1 to any desired number, the only limit being the size of the disks, and in practice it is desired to include on the disks marginal numbers running higher than those shown in the accompanying drawing. 60

65 Referring to the drawing by reference numerals 1 indicates the device comprising the lower disk 2 and the upper disk 3 pivoted centrally at 4 in the manner as shown in Fig. 3. The lower disk 2 is preferably 70 larger in diameter than the upper disk 3, so that the large marginal numbers 5 may be displayed thereon, although this construction is not entirely essential as the marginal numbers 5 on the lower disk may be 75 placed immediately around the pivotal point thereof, while the marginal numbers 6 on the upper disk may be similarly disposed adjacent the pivotal point. In this event the two disks 2 and 3 could be of equal diameter. 80 From this it will be understood that the marginal numbers hereinbefore and hereinafter mentioned may be disposed on the disks in the most convenient manner, so long as they are visible and can be 85 brought opposite.

The disk 2 having the marginal numbers 5 is preferably provided with a series of marks 7 while the upper disk 3 is preferably provided with a series of marks 8, 90 which marks on said disks should register in the manner as shown in Fig. 1 in order to insure the proper position of the upper disk in relation to the lower disk when any of the marginal numbers on the said disks are 95 brought opposite to each other for the purpose of indicating the sum, the difference, the result and the quotient of the said two numbers, said series of numbers being indicated by the numeral 5'. The marginal 100 numbers on the upper disk are preferably provided with the usual arithmetical signs 9 and the equal marks 10 and lines 11 passing therefrom to the openings 12 in the disk 3, so that the numbers on the lower disk 105 visible through the openings 12 are quickly connected by the eye with the marginal numbers on the upper disk in the manner as illustrated in Fig. 1.

Having thus described the invention it 110 will be noted from Fig. 1 that the openings 12 on the disk 3 are differently located in

said disk for each marginal number thereon, said openings on said upper disk corresponding with the numbers appearing on the lower disk which are the sums, the differences, the 5 results and the quotients of any of said marginal numbers on the lower disk with respect to any and all of the said numbers on the said upper disk in such manner that the openings on the said upper disk which are opposite a 10 certain marginal number thereon will always uncover certain numbers on the lower disk arranged at a certain predetermined point on the lower disk, in the manner as will be clearly apparent upon inspection of the accompanying drawing.

I lay no claim whatever to a calculating device in which only a single factor of two given numbers is indicated or uncovered by the calculator, as such a device is not within 20 the spirit of this invention, which is primarily designed as a mathematical educational device wherein a plurality of factors of two given numbers are simultaneously displayed or indicated.

Having thus fully described the invention what I claim as new and desire to secure by Letters Patent of the United States is—

1. A calculator of the type described including two relatively rotatable disks centrally pivoted, the lower disk containing a 30 series of marginal numbers, the upper disk containing a series of marginal numbers, the lower disk containing opposite each marginal number thereof the sums, the differences, the products and the quotients of said marginal number with respect to every marginal number appearing on the upper disk, the said upper disk being provided with an opening opposite each marginal number 35 thereon and in line with the numbers on the lower disk constituting the sum, the difference, the product and the quotient of said marginal number on the upper disk with respect to a marginal number on the lower disk, to simultaneously indicate the sum, the difference, the product and the quotient of any two marginal numbers upon a single 40 relative movement of the disks, the said opening opposite each marginal number on the upper disk being disposed in a different 45 position from the other openings therein substantially as described and for the purposes set forth.

Copies of this patent may be obtained for five cents each, by addressing the "Commissioner of Patents, Washington, D. C."

2. A calculator of the character described including a lower disk having marginal 55 numbers thereon, an upper disk pivoted thereto and having marginal numbers thereon, the lower disk being provided opposite each marginal number thereon with a plurality of series of numbers, the same 60 being the factors of said marginal number with respect to all of the marginal numbers on the upper disk, the said upper disk being provided with an opening opposite each marginal number thereon and in line with 65 the numbers on the lower disk corresponding with the factors of said marginal number in connection with all of the marginal numbers on the lower disk to simultaneously uncover a number of each plurality of series of 70 numbers on the lower disk opposite a marginal number thereon upon a single relative movement of the disks, the said opening in said upper disk opposite each marginal number thereon being disposed in said upper 75 disk at a different point from the other openings therein substantially as described.

3. A calculator of the character described including a lower disk and an upper disk pivoted together, each of said disks being 80 provided with marginal numbers adapted to be brought opposite to each other upon relative rotation of the said disks, the said lower disk containing opposite each marginal number thereon a plurality of series of numbers, 85 each series of numbers being the results or factors of said marginal number in connection with all of the marginal numbers on the upper disk, the said upper disk being provided with an opening therein opposite each 90 marginal number thereon to uncover a number in each of said plurality of series of numbers opposite each of the marginal numbers on said lower disk to simultaneously indicate a plurality of results or factors of any 95 marginal number on the upper disk in connection with any marginal number on the lower disk upon a single relative movement of the disks, substantially as described and for the purposes set forth.

In testimony whereof, I affix my signature, in presence of two witnesses.

CHARLES HUGH DUFFY.
